UNITED STATES PATENT OFFICE.

WILLIAM B. STODDARD, OF STAMFORD, CONNECTICUT, AND VAMAN B. KOKATNUR,
OF NEW YORK, N. Y., ASSIGNORS TO PILOT LABORATORY, INC., OF ARLINGTON,
NEW JERSEY, A CORPORATION OF NEW JERSEY.

PROCESS OF AND COMPOSITION FOR BLEACHING.

No Drawing. Application filed June 7, 1927, Serial No. 197,226. Renewed December 19, 1927.

This invention relates to a process of and composition for bleaching organic materials, both animal and vegetable such as flour and other milling products, oil seed meals, soaps, 5 waxes, oils, egg yolk, etc., and in its preferred embodiment relates more particularly to a process of and composition for bleaching such organic materials wherein there may be advantageously employed organic 10 peroxids which heretofore have been considered too weak or too slow in their bleaching action for such use, or which normally have no bleaching action.

An important object of this invention is 15 to make effective use in the bleaching art of inexpensive but normally inactive or relatively inactive organic peroxids.

Another object of the invention is to make 20 effective use in bleaching operations of substantially all of the available oxygen in organic peroxidized compounds.

A further object of the invention is to 25 increase the rapidity of the bleaching action of organic peroxid compounds.

A further object of the invention is to 30 secure the rapid bleaching of organic materials without over-bleaching them whereby for example, the blue tone of over-bleached flour is avoided.

A further object of the invention is to 35 provide an organic peroxid bleaching composition which is more efficient and effective pound for pound than organic peroxids heretofore used or suggested for use as bleaching agents, whereby a materially smaller amount of bleaching material may be employed to effect thorough bleaching than heretofore has been possible.

A further object of the invention is to 40 provide a substantially solid bleaching agent employing as an ingredient thereof an organic peroxid compound which is normally in a semi-solid or even liquid condition and accordingly normally unsuitable for use for bleaching some organic materials, notably flour and other milling products.

A further object of the invention is to 45 increase the solubility of organic peroxid bleaching agents in vehicles, usually oils, in which coloring matters are dissolved as for example, the chromophoric oils of flour, seed meals and the like. By chromophoric oils, we mean oils which contain coloring matter

such for example as carotin, in solution or suspension therein.

Other objects and advantages of the invention will become apparent from the following description.

Various organic peroxid compounds heretofore have been proposed for use in the 55 bleaching of cereals and other foodstuffs but many of them such as phthalyl peroxid, acetyl peroxid, succinyl peroxid or mixed peroxids such as benzoyl-fumaryl peroxid and benzoyl-acetyl peroxid and the per-acids 60 of the above, have been found to have very small bleaching action per unit of their 65 available oxygen. Therefore though capable of being manufactured economically and containing a higher percentage of available 70 oxygen than peroxids heretofore used in bleaching, such peroxids have found little or no application in the bleaching art.

We have discovered that inactive or relatively inactive organic peroxidized compounds can be made into active and efficient 75 bleaching agents by mixing with them relatively small quantities of other active organic peroxid compounds and particularly those produced from organic materials 80 which are constitutionally similar to some of the constituents of the material to be bleached. Thus for example, in bleaching materials wherein the coloring matter is dissolved in oil, a fatty acid peroxid and preferably a fatty acid peroxid or peroxidized compound produced by the peroxidation of 85 a fat or oil, such as cocoanut oil or the acids therefrom, may be advantageously added to an inactive or relatively inactive organic 90 peroxid compound and so used will act as an activator to increase its bleaching action.

We also have found that the addition of 95 an activating organic peroxid compound to an inactive or relatively inactive organic peroxid, aside from acting on the inactive peroxid compound to assist or activate it in giving up its oxygen also, in the case of oil insoluble organic peroxids, brings about a 100 solution of the inactive per-compound in the chromophoric oil contained in the material to be bleached. In a case where the coloring matter to be bleached is dissolved in a chromophoric oil it will readily be seen that the 105 solubility of a bleaching peroxid in the chromophoric oil of the materials to be bleached,

brings about a condition of maximum bleaching effect, because of the intimacy of contact. For this reason, the solubility of a bleaching peroxid in oil has a direct relation to the bleaching power. Thus an activating peroxid which itself is oil soluble, not only activates the inactive or relatively inactive peroxids but solubilizes them in the oil or oily constituents in which such inactive peroxy compounds are normally insoluble or relatively insoluble.

In the production of our improved bleaching composition we may advantageously proceed as follows:

In a suitable vessel fitted with any desired means of vigorous agitation are placed 225 liters of 7½ per cent. hydrogen peroxid. This is then diluted by adding about 200 liters of water. To this solution is then added 246 kilograms of sal soda. The mixture is then agitated and cooled to about -5° C. To this solution while being vigorously agitated is gradually added within about 10 minutes a mixture of 87.5 kilograms of a mixture of two gram moles of benzoyl chlorid and one gram mole of fumaryl chlorid and 12.5 kilograms of any fatty acid chlorid, preferably a chlorid of a soap forming fatty acid, e. g., capryl chlorid, lauryl chlorid, oleyl chlorid. During this addition the temperature is held as near 0° C. as possible. The mass is agitated until the odor of the acid chlorids disappears. This ordinarily requires from 10 to 30 minutes. Upon the completion of the reaction the mixture of peroxids formed is filtered, washed with water, dried with or without the addition of inert fillers, e. g., calcium sulfate, magnesium sulfate, starch or the like and ground. It is then ready for use as a bleaching agent.

It is to be understood that the details of procedure, the temperature limits, ingredients and proportions of ingredients may be widely varied as will be obvious to anyone skilled in the art. Thus in a modified process of producing our bleaching composition we add a mixture of benzoyl chlorid and fatty acid chlorid or chlorids to other chlorids, as for example benzoyl and fumaryl chlorids, or to succinyl, phthalyl or citryl chlorid and then carry out the peroxidation of the mixed chlorids as described above. Instead of using a single fatty acid chlorid with other organic acid chlorid or chlorids in the peroxidation step we may use a mixture of two or more fatty acid chlorids.

We also may produce our bleaching composition by intimately mixing an active organic peroxidized compound preferably but not necessarily, a fatty acid peroxid or a mixture of fatty acid peroxids, in suitable proportions with the organic peroxy compounds to be activated, which in the most advantageous practice of our process will be an inactive, nonbleaching or a relatively

nonbleaching organic peroxid or peroxidized compound.

By changing the proportions of the various acid chlorids in the mixture before peroxidation, the physical and chemical properties 70 of the resulting peroxy compounds are widely changed. Thus some of the peroxid compounds are solid, some oily solids and some even oils. This is perhaps due to eutectic mixtures formed. In the practice of our 75 process we may employ these liquid or semi-liquid organic peroxids in admixture with activating organic per compounds, such for example as the peroxids or per acids of fatty acids, notably peroxids of the higher 80 or so-called soap forming fatty acids.

Although in the illustrative example given above we have used as an activating peroxid a peroxid of a so-called soap forming fatty acid it is to be understood that fatty acids 85 other than the higher fatty acids or so-called soap forming fatty acids may be used. For example, in place of the capryl peroxid, lauryl peroxid, or oleyl peroxid or mixtures thereof, we may employ as the activating 90 peroxid, crotonic acid peroxid and valeric acid peroxid or mixtures thereof.

We also may use as the activating peroxids, peroxids of non-fatty acids such for example, as benzoyl peroxid, cinnamic acid peroxid, 95 phenylacetyl peroxid, or mixtures thereof. In using activating organic peroxids with relatively inactive organic peroxids we have found that satisfactory and highly economical results are obtained by mixing with the 100 relatively inactive peroxid from 5 to 10 per cent by weight of the activating peroxid and in the employment of such mixture we have found that we may advantageously employ from one-half to one-sixth of the 105 quantity of bleaching agent commonly employed when using other organic peroxids, such for example, as benzoyl peroxid in the bleaching operation.

Even a somewhat active peroxid like 110 benzoyl peroxid or its homologues, can be further activated when intimately mixed with about 5-10 per cent of a fatty acid peroxid such for example as butyric acid peroxid, caproic acid peroxid or capric acid 115 peroxid. When so activated an amount of peroxid composition equivalent to about .004 per cent by weight of the flour or other material to be bleached is enough to give a bleaching effect equal to that produced by 120 using .025 per cent by weight of the unactivated benzoyl peroxid.

We also may employ as the activating agent a per-compound of an inorganic material such as calcium peroxid, sodium 125 peroxid, ammonium per-sulphate, sodium chlorate and other per-compounds.

In its broadest aspect our invention involves the use of any activating per-compound to activate any other less active or- 130

ganic peroxid whereby the bleaching action of the less active peroxid is enhanced.

We have found that we may employ as low as 1 or 2 per cent of the activating per-
5 compound, as for example, a fatty acid peroxid such as those above referred to, in admixture with a sluggish or less active organic peroxid such for example, as phthalyl or fumaryl peroxid, and obtain a bleaching
10 agent having greatly enhanced efficiency. By increasing the proportion of the activator peroxid to about 15 per cent of the mixture, in the case where a peroxid of a fatty acid is employed, the resulting product has still
15 greater bleaching efficiency. For example, one pound of such mixed peroxid compound intimately mixed with 30,000 pounds of flour and allowed to stand at ordinary atmospheric temperatures for 48 hours, pro-
20 duces remarkably rapid, effective and thorough bleaching and there is little tendency to produce the undesired blue tone frequently caused by overbleaching with other organic peroxid bleaching compositions. It
25 should be noted that some activator peroxids such as the fatty acid peroxids, need to be used only in the proportion of from 1 to 2 per cent. of the weight of the inactive or less active peroxids. Other activating per-
30 oxids than the fatty acid peroxids are prefer-
ably used in higher proportions as for ex-
ample, in proportions of from 5 to 20 per
cent by weight of the peroxid to be activated.
35 Each activator peroxy compound has cer-
tain definite proportions to give optimum
activating effect with each individual in-
active or less active peroxy compound. These
40 proportions, as is evident, must necessarily
vary between wide limits, depending upon
the nature of the activator peroxid, that of
the peroxy compound to be activated and
the materials to be bleached but in all cases
45 which we have investigated the addition
of the activating peroxid in the proportion
of from 5 to 10 per cent by weight of the
less active peroxid has given satisfactory
and economical results.

We have found that the fatty acid per-
50 compounds preferably peroxids made by the
peroxidation of soap forming fatty acids or
from organic acids which occur in natural
fats and oils, not only have pronounced
bleaching action but possess marked activat-
55 ing influence upon less active, inactive or
sluggish organic peroxids or per-compounds.
We have obtained particularly satisfactory
results by the use of the peroxidized higher
fatty acids notably caproic, oleic, and the
like.

60 The fatty acid per-compounds are particu-
larly advantageous for use as activators in
in our improved bleaching compositions by
reason of their peculiar quality of rendering
other organic per-compounds normally in-
65 soluble in the color carrying oils of organic

matters, soluble in such oils, whereby the bleaching of oils and organic materials whose oily content contains coloring matter may be rapidly and satisfactorily effected.

By the term "inactive organic peroxids" 70 we refer to those per-compounds whose available oxygen content is not readily given up in the bleaching operation and which are normally ineffective in bleaching organic materials when merely intimately mixed 75 therewith. The terms peroxid, per-compound, peroxy compound, peroxidized compound, etc., as used herein include organic peroxids, per-acids, per-acid salts and like per-compounds.

80 Many of the inactive or relatively inactive types of organic peroxids contain more available oxygen than the benzoyl peroxid heretofore used in bleaching flour and other food stuffs and are more economical to make. 85 Acetyl, fumaryl and succinyl peroxids for example, contain more than twice as much available oxygen as benzoyl peroxid. Such inactive or relatively inactive peroxids could not be made available for bleaching organic 90 materials without the use of an activator.

While our invention is intended primarily for making use as bleaching agents of organic peroxid compounds which are inactive or relatively inactive in bleaching and par-
ticularly such peroxids as have a high con-
tent of available oxygen, it will be under-
stood that our invention is adapted to be
successfully employed in connection with
other organic peroxy bleaching agents 100
whereby, by the use of an activating per-
oxidized compound as hereinbefore set forth,
such organic peroxids act more rapidly and
effectively in bleaching than when used with-
out the employment of the activating or-
ganic peroxid therewith.

This application is a continuation in part
of our application Serial No. 177,218, filed
March 21, 1927, for process of and composi-
tion for bleaching with certain additional 110
subject matter embodied therein.

While we have described in detail the preferred practice of our invention and the preferred proportions of ingredients it is to be understood that our invention is not 115 limited thereto nor otherwise than as set forth in the subjoined claims.

We claim:

1. A process of bleaching comprising sub-
jecting the material to be bleached to the 120
action of an organic peroxid compound and
an activating per-compound therefor,
whereby the effectiveness of the bleaching
action of the organic peroxid compound is
increased.

125 2. A process of bleaching comprising sub-
jecting the material to be bleached to the
action of an organic peroxid compound and
an activating organic peroxid therefor,
whereby the effectiveness of the bleaching 130

- action of the first organic peroxid compound is increased.
3. A process of bleaching comprising subjecting the material to be bleached to the action of a normally relatively inactive organic peroxid compound and an active organic per-compound, the active organic per-compound being an activator for the relatively inactive organic peroxid compound in the bleaching operation.
4. A process of bleaching which comprises subjecting the material to be bleached to the action of a normally relatively inactive organic peroxid, and an activating peroxid therefor, which activating peroxid comprises a fatty acid peroxid.
5. A process of bleaching comprising subjecting a solid material to be bleached to the action of a normally nonsolid relatively inactive organic peroxid compound and a solid organic peroxid in such proportions as to produce a solid mixture, one of said peroxid compounds being an active bleaching agent.
6. A process of bleaching comprising subjecting a chromophoric oil containing material to be bleached to the action of an organic peroxid which is insoluble in said oil and an organic peroxid which is soluble in said oil.
7. A process of bleaching comprising subjecting a chromophoric oil containing material to be bleached to the action of a relatively inactive organic peroxid compound which is insoluble in said oil and a peroxidized acid occurring in natural fats and oils which peroxid is soluble in said oil.
8. A process of bleaching comprising subjecting the material to be bleached to the action of a normally relatively inactive organic per-compound and a peroxid of an acid of the type occurring in animal and vegetable fats and oils.
9. A process of bleaching comprising subjecting a chromophoric oil containing material to be bleached, to the action of a relatively inactive organic peroxid and a higher fatty acid peroxid compound which is soluble in said oil.
10. A process of bleaching comprising subjecting a chromophoric oil containing material to be bleached, to the action of a normally relatively inactive organic peroxid compound which is insoluble in said oil and an activator therefor comprising an active higher fatty acid peroxy compound which is soluble in said oil.
11. A bleaching agent comprising a relatively inactive organic peroxid and an activating peroxy compound.
12. A bleaching agent comprising a relatively inactive organic peroxid compound and an active organic peroxid compound, the active organic peroxid compound being an activator for the normally inactive organic peroxid compound.
13. A bleaching agent comprising a non-solid, relatively inactive organic peroxid compound which is insoluble in the oil of the material to be bleached, and an active organic peroxid which is soluble in said oil.
14. A bleaching agent comprising a relatively inactive organic peroxid which is insoluble in the oil of the material to be bleached, and an organic peroxid compound which is soluble in said oil.
15. A bleaching agent comprising a normally oil insoluble relatively inactive organic peroxid and an oil soluble active organic peroxy compound.
16. A bleaching agent comprising a relatively inactive nonsolid organic peroxid compound and a solid active organic peroxid.
17. A bleaching agent comprising a relatively inactive organic peroxid and a fatty acid peroxid compound.
18. A bleaching agent comprising a normally inactive organic peroxid and peroxy compound of acids of the type occurring in animal and vegetable fats and oils.
19. A bleaching agent comprising a normally relatively inactive organic peroxid compound which is insoluble in the oil of the material to be bleached, and an activator therefor comprising a fatty acid peroxid which is soluble in said oil.
- In testimony whereof we affix our signatures.

WILLIAM B. STODDARD.
